FIG. 1 is a top plan view of the dispenser top for a pressure can of my design, wherein the sides are smooth. FIG. 2 is a side elevation thereof.

FIG. 3 is a front elevation thereof.

FIG. 4 is a rear elevation thereof.

FIG. 5 is a side elevational view of a modified form of the design of FIGS. 1-4 wherein the sides are fluted.

FIG. 6 is a top plan view of the modified form.

FIG. 7 is a front elevation of the modified form.

FIG. 8 is a rear elevation of the modified form.

This application is a continuation of my prior applications D-73,868, filed Mar. 7, 1963 and D-76,640, filed Sept. 19, 1963, both of which are now abandoned.

I claim:

The ornamental design for a dispenser top for a pressure can, as shown and described.
